UNITED STATES PATENT OFFICE

2,107,837

APPARATUS FOR FORMING TUBULAR ARTICLES

Willis C. Robbins, Wakefield, Mass., assignor to
Metropolitan Sewing Machine Corporation,
Nyack, N. Y., a corporation of Delaware

Application June 13, 1934, Serial No. 730,378

6 Claims. (Cl. 112—63)

This invention relates to improvements in apparatus for forming tubular articles, particularly filled and unfilled belts for wearing apparel.

In most previous efforts belts were formed by folding a strip upon itself and infolding the edges of the strip, then sewing said edges together with a stitch which would be exposed in the final article; and in those forms of belts which were sewed inside out and then turned in order to obtain concealed stitching it was necessary to manually turn the belts right side out with long bar like tools.

Heretofore it has usually been necessary to separately iron the tubular article with a separate and disconnected operation subsequent to sewing the tubular article, and so far as is known, no unitary process or apparatus has been provided which will completely fabricate (fold, sew, turn, moisten, and iron) a belt at one time.

It is an object of the present invention to provide an improved process for forming tubular articles, which will facilitate the manufacture and improve the quality thereof, particularly belts for apparel.

A further object is to provide a unitary mechanism adapted to perform a plurality of steps in the manufacture of a tubular article; viz., do in a single machine and with a single operator that which has heretofore been done on separate machines and by separate operators, to the end that a more uniform and economical product may be obtained.

It is a further object of the present invention to provide a tubular article forming apparatus which will be economical, compact, and readily accessible for initial loading, for adjustment, and for observation of the article as it is being fabricated.

Yet another object is to provide an apparatus which will make possible the practical and economical forming of belts from waste materials.

Features of the present invention include the provision of a novel form of guide attachment for folding and guiding a strip relative to the sewing mechanism; apparatus for turning the tubular article right side out; apparatus for removing wrinkles from the tubular article; means for directing a tubular article, which is originally sewed in a direction away from the operator, subsequently toward the operator again for satisfactory visual inspection—thence, rearwardly of the machine again for subsequent operations; apparatus for ironing the finished article; means for filling the tubular article; and a novel mechanism

for moistening the tubular article prior to the ironing operation.

Other objects, features, and advantages will appear hereinafter.

The present invention comprises details of construction and combinations and arrangements of parts which will be fully described hereinafter, and then specifically defined in the appended claims.

The present preferred embodiment of the invention is illustrated in the accompanying drawings, in which:

Figure 1 is a top plan view of the complete machine with a fragment of the sewing mechanism head removed.

15

Fig. 2 is a side elevation.

Fig. 3 is a front view.

Fig. 4 is a perspective view of the work guide.

Fig. 5 is a detail of the atomizer.

Fig. 6 is a sectional view of a modified form of heating and ironing device.

Fig. 7 is a sectional view taken on line 7—7 in Fig. 4.

Fig. 8 is a sectional view similar to Fig. 7 but of a slightly modified form of guide.

25

Referring now in detail to the drawings, the present invention comprises a base plate 11, supporting a sewing mechanism 12 near the front thereof. This sewing mechanism may be of almost any conventional type and for illustration 30 is of the well known Metropolitan type including a frame 13, suitably bolted to the base, with an overhanging arm 14 supporting a needle bar 15 and presser foot 16, and having a lower section 17 supporting a looper 18 and a feed dog 19.

35

Operating mechanism for the needle bar 15, looper 18, and feed dog 19 may be of any usual type associated with any of the well known direct motor drives or may include a pulley 20 at one side of the sewing mechanism having a suitable 40 belt connection through holes 21 to a prime mover under the base plate 11.

A strip 22 of cloth or any other material on a reel 23 rotatable on a standard 24 is, according to the present invention, both folded and guided to the sewing mechanism 12 in a very efficient way, in a manner to permit ready accessibility to all the operating parts. Also the present invention makes possible close visual inspection of the product by the provision of a novel and very efficient guide 25, which permits mounting the strip supply roll 23 at an angle to the line of stitching and which directs the strip rearwardly of the machine during the sewing, then forwardly thereof.

50

55

Preferably the guide 25 is secured to a cloth plate 26 by screws 27, and comprises an inlet channel member 28 of substantially U-shaped in cross section adapted to fold the strip and align 5 the edges 29 relative to each other and particularly to direct the strip 22 from a plane at an angle to the line of stitching to the plane of the line of stitching. At its inner end the inlet channel member 28 aligns with an outlet channel member 30 also of substantially U-shape in cross section adapted to fold the strip about a return tube 31 with the edges of the strip directly in the line of stitching, as shown in Fig. 7. The tube 31 may be U or variously shaped but 10 is preferably made as shown. A notch 32 on the guide clears the presser foot 16, needle 33 and feed dog 19 to permit a usual feeding action. The inlet channel member 28 may be dispensed with but its use insures a better product. Relationship 15 between the inlet channel member 28, outlet channel member 30 and return tube 31 is such that the strip is neatly folded at its center and the edges thereof are properly directed to stitch forming parts of the sewing mechanism 12.

25 The return tube 31 is a particularly novel part of the guide 25. It is supported in spaced relation to the outlet channel member 30 by fingers 34 thereon secured to the guide 25, and may have other similar fingers extending to the outlet 30 channel member walls '30' for added rigidity. The tube serves as a master about which the strip is folded and as a guide prior, during, and subsequent to the formation of a line of stitching 35 making the strip 22 into an inside out fabric 35 tube or belt 22' and also serves to fold the formed belt right side out and direct it toward the front of the sewing mechanism again. With the outlet tube 28 it serves to guide the strip absolutely parallel with the line of stitching and 40 insures uniform products.

Subsequent to the formation of the line of 45 stitches 35 and making of the strip 22 into a tubular article such as belt 22', the belt is moved rearwardly of the sewing mechanism 12 then curled back upon itself or turned right side out to conceal the line of stitches as shown at G by being fed or pulled back through the return tube 31 toward the front of the sewing mechanism as may be seen best in Figs. 1 and 7, 50 to facilitate visual inspection. The expression "tube" is intended to cover both a belt and any tubular strip made on this apparatus, and "belt" only those made for use on wearing apparel. Feed of the tube through the return tube and turning it right side out may be accomplished 55 manually by having an operator pull the tube. However, this is done automatically according to the present invention through the provision of a puller or other feeding device 36 secured to the 60 base 11 by screws 37 preferably at the rear of the sewing mechanism with a pair of feed rollers 38, including lower and upper rollers 39 and 40 respectively located in slightly spaced relation side-wise to the line of stitching. A pair of standards 65 41 and 42 with a sleeve 43 and roller 44 respectively, in alignment with the return tube 31 and with the puller rollers 38, completes the mechanism for moving the stitched tube forwardly into the line of vision.

70 Rotation of the feed rollers 38 in proper peripheral ratio with feed of the dog 19 is accomplished through a driving connection 45 between the sewing mechanism 12 and a main drive shaft 46 of the puller feed device 36. As shown, this 75 driving connection comprises a crank arm 47 as-

sociated with an eccentric 48 on a main drive shaft 49 of the sewing mechanism, and at its other end has a suitable adjustable connection with a grip clutch 50 of the usual type for regularly connecting a puller feed device with a sewing mechanism. Since such driving connections are well known, detailed description will be omitted. Preferably the upper roller 40 is driven coordinate with the lower roller 39 through the provision of a gear (not shown) on the main 10 shaft 46 engaging and driving a gear 51 on the upper roller shaft 52.

As shown, the upper roller is yieldingly moved toward the lower roller as by a spring 55 pressing down on a collar 53 carried by a rod 54. A 15 lever 56, under the collar 53, connected to any suitable hand or foot lever is provided to lift the feed roller 40 from the bottom roller 39 to facilitate introducing the belt thereto.

If preferred, only one standard 42 and one 20 roller 44 as shown by dot and dash lines need be provided; dispensing with standard 41 and sleeve 43, in which event the roller is preferably made of larger diameter as shown by the roller 44' while the standard is located as shown by dot 25 and dash lines in Fig. 1 in order to have the rearward travel of the finished belt 22' out of the path of the stitch forming parts. When it is desired to use the sleeve 43 with this form of the 30 invention the sleeve 43 may be connected to the guide 25 by arms 43'.

Although the standard 41 may be provided with a roller, similar to the roller 44 in place of the sleeve 43, the latter performs an important 35 function about to be described. As the stitched tube or belt 22' is pulled from the return tube 31 it is somewhat round in shape and sometimes has wrinkles. The present invention provides an apparatus to remove the wrinkles and to initially flatten the belt again. This apparatus includes a 40 floating spreader 57 preferably in the form of a solid metal lug of substantially the same diameter as the inside of a stitched tube and tapered at each of the ends as shown in Fig. 4, to straighten out the wrinkles and to spread the tube prior to its 45 entrance into the sleeve 43 where it is initially formed flat again. The sleeve thus prevents the spreader from travelling with the belt, initially flattens the belt, and cooperates with the spreader to remove wrinkles.

The apparatus so far described is capable of 50 folding and guiding flat strip material to the sewing mechanism, to form a tube, then to turn the tube right side out, to remove the wrinkles, flatten the tubular article, and to pull it through the 55 machine.

The present invention also provides mechanism to impregnate the belt 22' with steam, liquid, or a wax-like powder to moisten or charge it, and 60 novel mechanism to iron it automatically as it is fed through the machine. In one form this impregnation may be accomplished through the provision of a container 58 with any suitable material secured to the frame of the puller feed device 36 by screws 59 and provided with a pipe 60 and nozzle 61, and with a pet-cock 62 adapted to regulate the flow of the material to the article. The pipe 60 may be connected to any suitable 65 source of steam. Also the nozzle 61 may be located at 61' to discharge on the inside of the belt where it reverses to provide a longer travel or time for impregnation to occur and so that the return tube 31 forms a chamber to insure thorough 70 impregnation. Preferably an air supply 63 is pro- 75

vided to force and apply the liquid or powder in the form of a fine spray 64.

For this purpose the present invention provides a cylinder 65 on a bracket 66 secured to the arm 14 in alignment with a piston 67 on the top end of the needle bar 15. When the needle bar and piston are in the lowered position the top of the piston is below the air entrance hole 68 so that the cylinder becomes filled with air, and as the piston is moved upwardly, the air in the cylinder is driven down through a pipe 69 to force the material out of the nozzle 61 in the form of a fine spray. As the needle bar is reciprocated at a high speed, the air forced down through the pipe 69 tends to suck more liquid or powder down through the pipe 60 thereby indirectly regulating or varying the amount as the speed of the stitching and feed of the belt is increased or decreased. This variable effect is more positively achieved through the provision of an atomizer 10 and container 11 which may be suitably mounted so that the nozzle thereof overlies or underlies the belt in any desired location. Thus, the air may be used to draw moistening or charging material from a container located below the belt or discharge nozzle to prevent leakage while the sewing machine is stopped.

Subsequent to the operation of moistening, the belt 22 is ironed, preferably with the application of heat. As shown in Figs. 1 and 2, an ironing device 12 provided by the present invention comprises a heated table 13 secured to the feed device 36 by screws 74. Preferably this table is somewhat hollow on the inside as indicated by the dotted lines 75, and is provided with a pair of holes in the side wall thereof, adapted to receive and support a substantially U-shaped heating element 76, best seen in Fig. 6. Current is received through a power line 11 thence through a variable resistance 78 and wires 79 and 80 to resistance wires suitably wound on the U-shaped member 76. The ironing device is completed through the provision of a presser member 72 pivoted on the shaft 52 and yieldingly forced toward the heated table 13 by a spring 81.

Thus, the present invention provides a very satisfactory apparatus adapted to moisten and to heat and iron the belt automatically and concurrently with the other operations of sewing, folding, and feeding the belt.

In some instances it is preferred to provide filler within the belt in order to give it thickness for appearance and for added strength. The present invention provides for automatically filling the tube as it is formed by the sewing mechanism 12, and prior to the ironing operation, so that the filler may be properly flattened relative to the final contour of the belt. To this end, an endless strip of filler 83 of felt, semi-loose cotton or other material, mounted on a suitable reel or in a supply box underneath the base 11, is passed upwardly through an aperture 84 and is directed into the belt 22 at the rear end of the return tube 31 as the belt is initially turned right side out and pulled back through the return tube. Thus, the belt, as it is squeezed together by the return tube, seizes and pulls the strip of filler from the source of supply in exact proportion with the feed of the belt. When the belt is to be so filled, the floating spreader 57 is no longer used. The filler may be of somewhat spongy or resilient material so that it serves to expand the belt as it leaves the front end of the return tube, and thereby remove the wrinkles prior to the belt passing into the sleeve 43, ironer device 12, and between the feed rolls 38. This

filler 83 may also be in the form of a single or double coated adhesive tape or gummed strip, for example like that used regularly to cement the hem in the bottom of trousers or for patching, which, when heat or moisture is applied will cause the fabric to adhere and prevent any possibility of wrinkling and will also stiffen the belt.

A modified form of ironing device 85 is shown in Figs. 1 and 6 comprising the same heating element 76 applied to the roller 39 of the puller feed device 36 in a novel manner. The lower roller 39 is hollowed as at 39' to accommodate the U-shaped body 76' of the heating element, and a frame wall 36' is provided with apertures 86 adapted to receive and hold the element. Thus, the lower roller may be conditioned to form a heating table and the upper roller cooperates as a presser member to heat and iron the belt 22 at the same time that it pull feeds.

In fabricating the tube with the preferred arrangement of the present invention the strip 22 is passed through the inlet channel member 28 which folds the strip upon itself right side out, and subsequently the outlet channel member 30 and return tube 31, as the reversal of the right angle feed takes place, turns the strip right side in. Thus, the strip is folded right side out when in the position "A", is folded right side in when in the position "B", and subsequently assumes the right side out position again as it enters and emerges from the return tube as at "C" and "D", reverses its direction of feed at the position "E" and again reverses its feed at "F". It is apparent then that the tube 22 with the concealed stitching is preferably made by travelling in five directions. The several arrows in Fig. 1 show the direction of travel. By thus forming a belt, manufacturing cost is considerably reduced, because waste materials may be secured together end-to-end even though the edges are rough and uneven, for these edges are subsequently concealed when the tube is turned right side out. In fabricating belts from waste materials it is necessary to have a closer check or control of the product, and the present invention with its feed into the line of vision is therefore especially advantageous.

It is within the purview of this invention to have the puller feed device 36 and either of the two forms of the ironing devices 12 or 85 and associated moisteners in front of the sewing mechanism 12 or to otherwise position these various mechanisms relative to each other, but for convenience of operation the arrangement shown is now preferred.

It is also within the purview of this invention to make a belt 88 with folded-in edges 89 and exposed stitches 90 by merely providing return bends 91 on the modified outlet channel member 94 as shown in Fig. 8. When this type of belt is made the puller feed device 36 is fastened to the base 11 in the position shown by dot and dash lines 92 so that the puller rolls 38 will be in a direct line with the belt 88 as it is moved rearwardly of the machine. Thus, the belt is formed without the need of folding it right side out, and in this direct passage to the rear of the machine may be moistened and ironed with the apparatus and the methods already described in detail.

If it is desired to load or fill this form of the belt, the filler 83 is passed upwardly of the base from its source of supply through a hole 93 in the front of the machine, then passed rearwardly through the return tube 31 into the belt as it leaves the rear end of the attachment 25, and

when once started is automatically pulled from the source of supply with the belt 88' by the feeding device.

Although the main purpose of this machine is 5 to sew and iron various types of belts for wearing apparel, it may be used advantageously to form other tubular articles. Variations and modifications in addition to those described in detail may be made within the scope of this invention, and portions of the improvements may 10 be used without others.

Having thus described the invention, what is claimed as new and desired to be covered by Letters Patent, is—

- 15 1. A tube sewing and turning apparatus comprising a sewing mechanism, a channel member adapted to fold a strip to maintain two edges of the folded strip in closely adjacent alignment and to direct the two edges parallel with the line of stitching; a tube within said channel around which the strip is folded; and means for pulling the stitched strip through the tube to turn it right side out.
- 20 2. A tube sewing and turning apparatus comprising a sewing mechanism; an inlet channel member for directing a strip at an angle to the line of stitching; an outlet channel member for folding a strip, maintaining two edges of the folded strip in closely adjacent alignment and for directing the two edges parallel with the line of stitching; and a tube within said outlet channel member around which the strip is folded for stitching and through which the stitched tube is turned right side out.
- 25 3. A tube sewing and turning apparatus comprising a sewing mechanism including a regular feeding means; an inlet channel member for directing a strip at an angle to the line of stitching; an outlet channel member for folding a strip, maintaining two edges of the folded strip

in closely adjacent alignment and directing the two edges parallel with the line of stitching; a tube within said outlet channel member around which the strip is folded for stitching and through which the stitched tube is subsequently turned 5 right side out; and a feed device associated with the sewing mechanism adapted to pull the stitched strip through the tube coordinately with the regular feed means of the sewing mechanism.

4. In a tube forming apparatus the combination of a sewing mechanism; a guide having a return tube upon which a strip is folded and sewed to form a stitched tube, and through which it is drawn for subsequent operations; a feeding mechanism on the sewing mechanism 15 adapted to feed the strip over the return tube; a feeding device adapted to draw the stitched tube through the return tube; a spreader adapted to be carried by the stitched tube; and a stationary sleeve intermediate the return tube and 20 the feeding device adapted to prevent the spreader from traveling with the tube.

5. In a tube forming and impregnating apparatus the combination of a sewing mechanism; a guide for directing a strip relative to the line 25 of stitching to form a stitched tube; means for directing charging material to the stitched tube; and means to force said charging material onto the tube including a piston on the needle bar and a cooperating cylinder.

6. In a tube forming apparatus the combination of a sewing mechanism; an inlet channel member adapted to fold a strip upon itself right side out and to direct the strip at an angle to the line of stitching; a tube; and an outlet channel 35 member associated with the inlet channel member but at an angle thereto adapted to fold the strip right side in about the tube and to direct it along the line of stitching.

WILLIS C. ROBBINS.
